(57) **CLAIM**

The ornamental design for the locking connector, as shown and described.

DESCRIPTION

FIG. 1 is a bottom left rear perspective view of the locking connector of our design;

FIG. 2 is a top right front perspective view thereof;

FIG. 3 is a left side elevation view thereof;

FIG. 4 is a ride side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The dashed broken lines depict portions of a locking connector that form no part of the claim.
